UNITED STATES PATENT OFFICE.

FRIEDRICH HUPE, OF THE UNITED STATES NAVY.

ROTARY STEAM-ENGINE.

1,153,086.

Specification of Letters Patent.

Patented Sept. 7, 1915.

Application filed April 12, 1915. Serial No. 20,852.

To all whom it may concern:

Be it known that I, FRIEDRICH HUPE, a citizen of the United States, stationed on board U. S. S. *Michigan*, have invented certain new and useful Improvements in Rotary Steam-Engines; and I do hereby declare the following to be a full, clear, and exact description of the invention, such as will enable others skilled in the art to which it appertains to make and use the same.

The present invention relates to improvements in rotary steam engines, and consists more particularly in an improved steam engine of the type embodying a rotor provided with a cam piston mounted in a cylinder having swinging abutments for co-operating with the rotor piston to drive the same.

It is an object of the present invention to provide an improved rotary steam engine constructed to be operated in either a forward or reverse direction and equipped with novel mechanisms for controlling the operation of the several swinging abutments and intake valves; such mechanisms being simple in construction and readily assembled and disassembled for repair and renewal of parts.

With these and other objects in view the invention consists in the novel details of construction and combinations of parts more fully hereinafter disclosed and particularly pointed out in the claims.

In the accompanying drawings forming a part of this application, and in which similar reference symbols indicate corresponding parts in the several views: Figure 1 is a side elevational view of an improved rotary engine constructed in accordance with the present invention. Fig. 2 is a vertical sectional view of the same. Fig. 3 is an enlarged top plan view, partly in section, of the improved engine. Fig. 4 is an end elevational view, partly in section, on the scale shown in Figs. 1 and 2; and Fig. 5 is an elevational view of one of the steam chests employed in conjunction with the improved engine.

Referring more particularly to the drawings, 1 designates a cylinder, cast or otherwise produced with a central partition 2 dividing the same to provide a pair of adjacent coaxial compartments inclosed by heads 3 and 4.

Journalized through the partition 2 and cylinder heads 3 and 4 is the main shaft 5

of the engine, roller or other bearings 6 being provided in journal boxes 7 formed in the cylinder heads to receive the same.

A pair of rotors 8 and 9 are mounted on the engine shaft 5 in the compartments to either side of the partition 2, and are formed with cam pistons 10 and 11, set at 180° apart, as indicated in Fig. 2, to admit of an impulse upon each half revolution of the engine shaft, as will be understood.

In each of the cam pistons 10 and 11 is formed a recess 12 for slidably receiving a packing 13, held projected in close contact with the cylinder walls by coil springs 14, as advantageously disclosed in Figs. 2 and 4.

The partition 2, as seen in Figs. 3 and 4, is provided with a vertical duct 15 and a series of lateral ducts 16 leading therefrom for delivering oil to the rotors 8 and 9, the engine shaft 5 and the several other moving parts.

At the upper portion, and to either side of the center of the cylinder 1, the same is constructed with enlargements 17 and 18 extending the width of the cylinder, and forming associated pairs of chambers 19 and 20 in communication with intake and exhaust ports 21 and 22, and for receiving swinging abutments 23 and 24. Each of the abutments 23 and 24 is formed with trunnions 25, as disclosed to advantage in Fig. 3, the same being journaled in the central partition 2 and respective cylinder heads 3 and 4. The abutments 23 and 24 are furthermore provided with channels 26 and 27 in communication with the exhaust ports 22 in the respective compartments of the cylinder 1; and said abutments are arranged to be maintained in retracted and inoperative position within their respective chambers 19 and 20, as shown to the left in Fig. 2, or may be released, as shown to the right in this figure, and permitted to swing inwardly and coöperate with the respective cam pistons 10 and 11 in a well understood manner.

The outer trunnions 25 of the several abutments 22 and 23, are extended beyond their respective cylinder heads 3 and 4 to receive arms 28 and 29, engaged at their free ends by headed rods 30 and 31 slidably mounted in sleeves 32 and 33 threaded for adjustment in sockets 34 and 35 formed on the cylinder heads 3 and 4.

Coil springs 36 and 37 are confined between the adjusting sleeves 32 and 33 and

the respective heads of the rods 30 and 31 for normally projecting the same, as seen to the right in Fig. 1, to lift the associated arm 28 and maintain the associated abutment 23, as shown in Fig. 2, in yielding engagement with the periphery of the rotor 8.

Each of the arms 28 and 29 on each of the cylinder heads 3 and 4, is formed with lugs 38 and 39 adapted for engagement by double throw latches 40, mounted to reciprocate in casings 41, and arranged to be manipulated by handles 42 projecting through slots 43 in the casings 41, and for limiting the movement of the latches in either direction.

Associated with the several intake ports 21, formed in each of the enlargements 17 and 18, are steam chests 44 and 45, bolted or otherwise removably secured thereto and arranged in communication with a source of steam or other active agent supply. The valve chests 44 and 45 are provided with guideways for receiving reciprocating valves 46 and 47, provided each with a pair of ports 48 and 49 arranged to register alternately with the intake ports 21 of the adjacent compartments, as indicated in Fig. 3. The valves 46 and 47 are connected to be actuated by stems 50 and 51, mounted through packing boxes in the valve chests 44 and 45 in any usual manner, and normally held by coil springs 52 and 53 in projected position. The outer headed ends of the valve stems 50 and 51 are freely engaged by levers 54 and 55 fulcrumed in pairs of ears 56 and 57 projecting from the respective cylinder heads 3 and 4, and provided at their inner ends with rollers 58 and 59 for coöperating with a cam 60 mounted to rotate with the engine shaft 5.

In operation, either pair of abutments 23 and 24 is selected, accordingly as the engine is to be driven in a forward or reverse direction, and the opposite set of abutments positively secured and maintained in their respective chambers 19 and 20 by the latch devices 40, as will be apparent from Fig. 1. The latch 40 is here shown to engage the lug 39 on the arm 29 of the abutment 24, the latter being held in retracted position, as will appear from Fig. 2, and against the influence of the spring 37 on the rod 31.

The opposite arms 28, on each of the cylinder heads 3 and 4, are released from engagement with the latch 40 and are moved upwardly by the coil springs 36, as indicated in Fig. 1, to swing the abutments 23, as shown in Fig. 2, into engagement with the periphery of the rotors 8 and 9, permitting the cam pistons 10 and 11 to successively engage and close the same at each half revolution of the engine shaft.

As the operation of the engine proceeds the cam 60 is rotated to oscillate the levers 54 and 55 to shift the valves 46 and 47, thereby alternately opening and closing communication of the ports 48 and 49 with the

respective ports 21 in the compartments of the cylinder 1. The steam or other active agent is thereby delivered successively to the compartments to either side of the partition 2, in conjunction with the respective abutments and cam pistons, to impress an impulse to the engine shaft at each half revolution thereof.

Connection is made from the source of steam or active agent supply to the steam chests 44 or 45, in accordance with the direction of the rotation of the engine, the opposite valve working idly. It will be understood that to reverse the direction of rotation of the engine, the arms 28 of the associated swinging abutments 23 may be depressed, and the latches 40 shifted by the handles 42 to engage the lugs 38 and maintain the same in position to retract the abutments. The corresponding abutments 24 will now be released, and will be moved by the springs 37 into engagement with the respective rotors 8 and 9, and will deliver the steam to the cam pistons 10 and 11 to rotate the same in the opposite direction.

It is obvious that those skilled in the art may vary the details of construction and arrangements of parts without departing from the spirit of my invention, and therefore I do not wish to be limited to such features except as may be required by the claims.

I claim:

1. In a rotary engine, the combination of a cylinder, a rotor journaled in said cylinder, a piston on said rotor, an abutment mounted to swing in said cylinder and coöperating with the piston on said rotor, an arm connected to said abutment, a socket on said cylinder, a rod slidably mounted in said socket and arranged to engage the free end of said arm, means for yieldably maintaining said rod in projected position, and means for confining said arm to hold the abutment in retracted position, substantially as described.

2. In a rotary engine, the combination of a cylinder, a rotor journaled in said cylinder, a piston on said rotor, a pair of abutments mounted to swing in opposite directions in said cylinder and coöperating with the piston to drive said rotor in opposite directions, arms connected to said abutments, sockets on said cylinder, rods slidably mounted in said sockets and engaging the free ends of said arms, means for yieldably maintaining said rods in projected position, and a latch for engaging said arms to maintain the same in position to hold the respective abutments retracted, substantially as described.

3. In a rotary engine, the combination of a cylinder, a rotor journaled in said cylinder, a piston on said rotor, a pair of swinging abutments mounted in said cylinder, arms connected to move with said

abutments, sockets on said cylinder, sleeves adjustably mounted in said sockets, headed rods mounted to slide in said sleeves and arranged with their headed 5 ends in engagement with the free ends of said arms, spring means confined between said adjustable sleeves and the heads of said rods for normally projecting the same, a casing arranged between said arms, and a 10 double throw latch mounted in said casing and arranged to be moved to engage either of said arms and confine the same in position to hold the respective abutment retracted, substantially as described. 15 4. In a rotary engine, the combination of a cylinder, a partition dividing said cylinder to provide a pair of coaxial compartments, a shaft journaled in said cylinder and extending into each of said compartments, a rotor mounted on said shaft in each of said compartments, a piston on each of said rotors, a pair of swinging abutments mounted in each of said compartments and coöperating with the respective piston to 20 drive the rotor in a forward or reverse direction, arms connected to move with said abutments and located without the cylinder, sockets on each of said cylinder heads, sleeves adjustably mounted in said sockets, 25 headed rods slidably mounted in said sleeves and arranged to engage the free ends of said arms, spring means confined between said sleeves and the heads of said rods for yieldably projecting the same, a casing on each of said cylinder heads disposed between said arms, and a double throw latch mounted in each of said casings and adapted to engage either of said arms and confine the 30 same against the action of said spring means 40 for maintaining the respective abutment retracted, substantially as described. 5. In a rotary engine, the combination of a cylinder, a rotor journaled in said cylinder, a piston on said rotor, a pair of enlargements formed on said cylinder, swinging abutments mounted in said enlargements and coöperating with the piston to drive said rotor in forward or reverse directions, arms connected to move with said abutments, sockets on said cylinder, rods slidably mounted in said sockets and engaging the free ends of said arms, spring means for normally projecting said rods, means for 45 50 adjusting the tension of said springs, a double throw latch for engaging and confining said arms against the influence of said spring means to hold the respective abutments retracted, intake and exhaust ports in said enlargements, valve chests removably connected to said enlargements, reciprocating valves mounted in said chests, a cam rotated from the engine, and oscillating levers actuated by said cam and arranged in connection to reciprocate said valves, substantially as described. 6. In a rotary engine, the combination of a cylinder, a partition dividing said cylinder to provide a pair of coaxial compartments, a shaft journaled in said cylinder, a rotor mounted on said shaft in each of said compartments, a piston on each of said rotors, enlargements one on each side of said cylinder and extending in communication with each of said compartments, a pair of oppositely acting swinging abutments mounted 70 one in each of the enlargements in each of said compartments and coöperating with the respective piston to drive the rotor in a forward or reverse direction, arms connected to move with said abutments, sockets on said cylinder heads, sleeves adjustably mounted in said sockets, headed rods slidably mounted in said sleeves and engaging beneath the free ends of said arms, coil springs confined between said sleeves and the heads 75 of said rods for normally projecting same, a casing mounted on each of said cylinder heads and disposed between said arms, a double throw latch mounted in each of said casings and adapted to be shifted into engagement to hold either of said arms confined and the associated abutment retracted, intake and exhaust ports in said enlargements, removable valve chests connected to 80 said enlargements, a reciprocating valve in each of said chests provided with openings adapted to register alternately with the intake openings of adjacent compartments, headed stems on said valve, springs confined between said chests and the heads of 85 said stems, levers fulcrumed on one of said cylinder heads and engaging the headed stems of said valve to reciprocate the same, and a cam on said shaft for oscillating said 90 95 levers, substantially as described. 100 105

In testimony whereof, I affix my signature.

FRIEDRICH HUPE.
